UNITED STATES PATENT OFFICE

133,317

DESIGN FOR A SHAPER

William F. Zimmermann, Maplewood, N. J., assignor to Gould & Eberhardt, Newark, N. J., a corporation of New Jersey

Application March 28, 1941, Serial No. 99,955

Term of patent 14 years

To all whom it may concern:

Be it known that I, William F. Zimmermann, a citizen of the United States, residing at Maplewood, in the county of Essex and State of New Jersey, have invented a new, original, and ornamental Design for a Shaper, of which the following is a specification, reference being had to the accompanying drawing, forming part thereof.

Figure 1 is a perspective view of a shaper showing my new design with portions of the base broken away for convenience of illustration, both sides of the base having substantially the same appearance;

Figure 2 is a side elevational view of the ram housing shown in full lines in Figure 1;

Figure 3 is a front elevational view, and

Figure 4 is a rear elevational view of said ram housing shown in full lines in Figure 1.

The dominant features of the design reside in the portions shown in full lines.

I claim:

The ornamental design for a shaper, substantially as shown and described.

WILLIAM F. ZIMMERMANN.
